Primary Examiner—Nelson C. Holtje*Assistant Examiner*—Jeffrey Asch*Attorney, Agent, or Firm*—Ladas & Parry**[57]****CLAIM**

The ornamental design for a telephone, as shown and described.

DESCRIPTION

FIG. 1 is a front view of my new design for a telephone; FIG. 2 is a top plan view of my new design;

FIG. 3 is a right side view of my new design;

FIG. 4 is a left side view of my new design;

FIG. 5 is a rear view of my new design; and,

FIG. 6 is a perspective view of my new design.

The broken line showing of a handset in FIGS. 1 and 2, and of features beneath the hangup switch in FIG. 6 are for illustrative purposes only and form no part of the claimed design.

FIG. 1

FIG. 2

FIG. 3
